PACKAGE

Joseph Hirsch Vineberg, Ottawa, Ontario,
Canada

Application September 15, 1938, Serial No. 230,132

3 Claims.

(Cl. 206—7)

This invention relates to packages for merchandise either of the folder or of the bag type, and more particularly to closure means for such packages. The invention relates to packages of paper or other suitable sheet material.

The object of the invention is to provide an improved package of simple and inexpensive construction, made of a minimum number of parts, and one which can be closed and opened by means of the simplest operations. The improved package is of increased durability and is constructed with a view to affording maximum protection to the contents.

According to the invention, in its broadest aspect, the improved package comprises two substantially similar connected rectangular areas and closure means comprising a pocket at one end of one of said areas and extending the entire width of said area and stiffening means on one end of the other area, and extending the entire width of that area, said stiffening means being so disposed as to be insertable into said pocket to close the package, and handle means being provided adjacent said stiffening means.

The invention further comprises the construction, combination and arrangement of parts hereinafter fully described and more particularly pointed out in the appended claims.

Referring now to the accompanying drawing which illustrates, by way of example, two convenient forms of the invention,

Figure 1 is an elevation of the blank from which one form of the improved package is made, together with the handle attached thereto,

Figure 2 is a perspective view of the package shown in Figure 1,

Figure 3 is a fragmentary sectional view on an enlarged scale on the line 3—3 of Figure 2,

Figure 4 is an enlarged sectional view on the line 4—4 of Figure 2,

Figure 5 is a perspective view of the folder package in closed position,

Referring to Figure 1, which shows the invention applied to a folder type of package, the blank of sheet material from which the package may conveniently be formed comprises a rectangular area 1 foldably connected at a fold line 2 to a similar rectangular area 3. Side flaps 4 are connected to area 1 along fold lines 5 and side flaps 6 may be connected to area 3 along fold lines 7.

An end flap 8 is connected to area 1 along a fold line 9, a slit 10 being formed in or adjacent to the central part of the latter fold line.

An end flap 11 is connected to the area 3 along

a fold line 12, this flap being formed with one or more parallel fold lines 13. One weakened fold line 13 is shown but more than one may be provided if desired. A slit 14, similar to the slit 10 is provided in the central part of the fold line 12.

Projecting through the slit 10 is a handle 15 formed with a finger slot 16 and preferably also formed with laterally projecting flanges 17 by means of which the handle is securely attached to the inner surface of the outer end of the area 1 by means of staples 18 or by stitching or any other suitable means. A garment hanger 19 may be formed integrally with the handle 15 as indicated in chain dotted lines in Figures 1, 2 and 3.

To complete the construction of this form of the invention, the flaps 6, if provided, are folded on to the area 3, the flap 11 is folded on itself about line 13 and the two layers of flap 11 are then folded about line 12 on to the area 3 and the inturned flaps 6. The folded flap 11 is then secured in this position by any suitable means such as staples 20 which pass through both folds of flap 11, the flaps 6 and the area 3, as near as possible to the bottom of the package as shown in Figures 2 and 4. A pocket 20a is thus formed under the folds of the flap 11 for a purpose to be described later.

The merchandise is placed on the area 1 and the side-closing flaps 4 are then folded inwardly to the position indicated in Figure 2. The stiffening flap 8 is then folded down on to the top part of the merchandise, and the area 3 is folded over on to the merchandise on area 1, or vice versa. The area 1 is then bent slightly to bring the handle 15 into the pocket 20a beneath the folds of the flap 11, and the area 1 is then released to permit the handle 15 to pass through the slit 14. The edge formed by the line 9 at the top of area 1 now engages in the pocket 20a and the package is thus held firmly in closed position as indicated in Figure 5. A closed ridge is thus provided at the top of the closed package, which effectively retains the package closed and protects the contents from dust or rain.

It will be understood that the foregoing description and accompanying drawing are given by way of example only and that any modifications within the scope of the appended claims may be resorted to without departing from the spirit of the invention.

What I claim is:

1. A packaging device comprising two substantially similar connected rectangular sections fold-

able one upon the other, a reinforcing multiply folded portion disposed along the entire width of one edge of one section and secured to said section to form a fixed receiving pocket, a slit in the fold line connecting the said folded portion to the said section, stiffening means connected along an edge of the other section and extending across the width of the package, the edge of said other section and said stiffening means being insertable in the fixed pocket, and a handle member on said other section adjacent said stiffening means disposed to pass through and project from said slit when the package is closed.

2. A packaging device of sheet material, comprising a pair of sections hingedly connected to one another and foldable one upon the other to enclose material therebetween, a free edge of one of said sections being folded upon itself to form a receiving pocket extending the entire width of said section, a slit in the fold line connecting said free edge to said section, means fastening said folded free edge to said section adjacent said fold line in fixed receiving position, said receiving pocket being adapted to receive the opposed free edge of said other section when said sec-

tions are folded one upon the other, handle means on said other section and extending beyond the free edge thereof, said handle means extending through said slit when said free edge of said other section is seated in said pocket.

3. A packaging device of sheet material, comprising a pair of sections hingedly connected to one another and foldable one upon the other to enclose material therebetween, a free edge of one of said sections having a plurality of parallel fold lines and being folded upon itself on said lines to form a receiving pocket extending the entire width of said section, a slit in the innermost of said fold lines which connects said
- 10 15 folded portion to said section, means for fastening said folded portion to said section in fixed receiving position adjacent said innermost fold line, said receiving pocket being adapted to receive the opposed free edge of the second section
- 20 25 when said sections are folded one upon the other, handle means on said second section and extending beyond said free edge thereof, said handle means extending through said slit when said free edge of said second section is seated in said pocket.

JOSEPH HIRSCH VINEBERG.
